COIN VENDING MACHINE

Stewart A. Maxwell, Walsall, England, assignor to Fisher & Ludlow Limited, Birmingham, England, a British company

Filed July 9, 1962, Ser. No. 208,229

6 Claims. (Cl. 221—114)

This invention relates to coin vending machines and is concerned with that type of machine having a magazine which is mounted in the casing of the machine, the magazine being formed with or carrying guides defining one or more columns in which the articles to be delivered by the machine can be stacked. In such a machine there is provided, in association with the or each column, release means which are operable in response to insertion of the correct coinage in the machine for delivering the lowermost article from the or a column, the remaining articles falling by gravity each time the lowermost article in the column is delivered.

Coin vending machines are frequently mounted on a wall or like support, or may stand in a shop doorway or like position and are therefore designed to be as compact as possible in order to cause minimum obstruction. However, in order to minimise the attention needed by the machine the maximum possible capacity must be provided, this also being desirable from the point of view of the owner or person renting the machine obtaining the maximum return from the machine. The result is that in many instances the combination of compactness with maximum capacity results in their being little space inside the machine between the top of the magazine and the top of the casing, so that refilling the magazine is a slow and tedious operation.

The object of the present invention is to provide an improved construction of coin vending machine which will not suffer from the above disadvantage and yet which will retain the same compactness and capacity as comparable known machines.

According to the present invention, I provide a coin vending machine of the above type, wherein the magazine and the casing are provided with co-operating means whereby the magazine may be supported in the casing in either an operative or a loading position.

The magazine mounting may be such that the magazine may be swung into an inclined position with respect to the casing in which the upper or loading end of the magazine is fully exposed. Alternatively, or additionally, the mounting may be such that the magazine can be lifted bodily from the casing.

Conveniently, the mounting for the magazine may include a pair of downwardly projecting extensions on the lower end of the magazine to engage the article release mechanism or other suitable part carried by the casing and co-operating formations at the upper end of the magazine and on the upper end of the casing, whereby the magazine can be hooked in position.

The release mechanism for delivering articles from the magazine will normally include a rotatable spindle and preferably the downward extensions are provided with open-ended elongated slots whereby they may engage over the spindle.

The co-operating formations on the upper end of the magazine on the upper end of the casing may conveniently comprise a slot formed in a suitable transverse member associated with the magazine and a stepped forwardly extending bracket secured to the casing, the stepped bracket providing for positive location of the magazine in its operative position and for temporary location thereof in an inclined or loading position.

2

The invention is illustrated in the accompanying drawings wherein,

FIGURE 1 is a front elevation, with part of the casing broken away, of a coin vending machine incorporating the invention.

FIGURE 2 is a side elevation with the side walls of the two covers broken away, both FIGURES 1 and 2 being broken so as to reduce the height of the machine.

FIGURE 3 is a detail showing the arrangement for holding the magazine against axial movement.

FIGURE 4 is a detail showing the article delivery mechanism.

FIGURE 5 is a detail showing an alternative form of magazine attachment bracket.

FIGURE 6 is a view similar to FIGURE 1 showing an alternative construction.

FIGURE 7 is a side elevation of the construction shown in FIGURE 6 and

FIGURE 8 is a detail showing the magazine attachment bracket.

In the form of my invention illustrated in FIGURES 1 to 5 the coin vending machine is of generally rectangular form and is adapted to be mounted on some suitable vertically extending support with its major axis vertical. The body of the machine is composed of a rear inner casing 10 which is of open box-like form and a front outer casing 11 which is also of open box-like form, the front outer casing 11 being of somewhat larger dimensions than the rear inner casing 10, so that the front outer casing is a sliding fit over the rear inner casing.

The front casing 11 carries the coin slot 12 and the delivery opening 13 through which articles are delivered from the machine whilst the rear casing 10 carries the coin selection mechanism 14 and the release mechanism

15 which latter mechanism is operable, after the correct coinage has been inserted in the machine, by means of a handle 16 disposed externally of the machine so as to effect delivery of an article to the delivery opening

13 and this rear casing 10 also carries the magazine 17 in which the articles are stored.

Suitable locking means are provided whereby the front and rear casings can be locked together, the arrangement being that when access is required to the machine for

55 maintenance or for replenishment the front casing can be unlocked from the rear casing and removed so as to expose the inside of the machine, the rear casing being screwed or otherwise secured to the supporting structure.

In order to facilitate the refilling thereof, the magazine 17 is detachably mounted on the rear casing 10. The magazine 17 is constructed of sheet metal and comprises a pair of channel section members 18 which are secured together by means of upper and lower straps 19, the open sides of the channel section members 18 being directed toward one another. With such an arrangement the base 20 of each member 18 constitutes a side of the magazine whilst the sides 20' of each member 18 constitute guides for the ends of the articles 21.

60 If desired channel section guide members may be secured to the bars 19 intermediate the members 18 so as to provide additional columns for the magazine.

Adjacent the lower end of the magazine 17 the front side of each member 18 is cut away for a suitable distance in order to permit delivery of articles forwardly of the magazine. The front sides, adjacent the cut away portions, are also curved forwardly as shown at 9 to assist in smooth delivery of the articles. The article delivery mechanism includes a spindle 22 which can be rotated by the handle 16 consequent upon operation of the release mechanism 15 and this spindle 22 has secured thereto an angle section plate 23 which is adapted to support the

lowermost article in the magazine and, in response to rotation of the spindle 22, to deliver the lowermost article to the delivery opening 13. This plate 23 is formed as an extrusion and comprises an article supporting arm 24 which is disposed horizontally in the "at rest" or non-operative position of the delivery mechanism, an attachment arm 25 which is adapted to be secured to the spindle 22 and a forwardly and upwardly extending guide arm 26 which retains the lowermost article in position.

The size and shape of the arms 24 and 25 will, of course, be selected in accordance with the type of article that is to be delivered from the machine.

As will be seen from FIGURE 4 the spindle 22 is provided with a portion which is of square section and secured to the opposite side of this square portion to that to which the attachment arm 25 is secured, is a blade member 27 which is adapted to engage the rear of the lowermost articles so as to project same into the delivery opening. Conveniently the blade 27 is secured to the spindle 22 by means of the same screws 28 as are used to secure the attachment arm 25.

The lower end of the magazine 17 is provided with a pair of downwardly extending projections 29 which are integral with the side walls 20 thereof, each projection 29 having in its lower edge an open-ended slot 30 whereby the projections may engage over the spindle 22 associated with the release mechanism. Such an arrangement supports and permits the correct location of the lower end of the magazine 17 with respect to the release mechanism 15 and also permits the magazine 17 to pivot around the spindle 22 of the release mechanism or to be lifted off the release mechanism.

In order to effect location of the upper end of the magazine 17, the upper transverse member 19 of the frame of the magazine is formed of right angle Z-section so that the two flanges 31 and 32 thereof are parallel with each other and at right angles to the web 33. The one flange 31 forms the attachment member to which the members 18 of the magazine 17 are secured, whilst the other flange 32 abuts against the base of the rear casing 10 when the magazine is in its operative position.

The other or rear flange 32 of the upper transverse member 19 extends upwardly with respect to the magazine 17 and is provided intermediate its ends with a slot 34 through which passes an attachment bracket 35 secured to and extending forwardly from the base of the rear casing 10. This attachment bracket 35 is of Z-section, the one end limb 36 thereof being welded or otherwise secured to the base of the rear casing 10. The transverse limb 37 is disposed so that it is somewhat downwardly inclined, and is cranked a short distance forwardly of the limb 36, so as to provide a vertical or substantially vertical shoulder 38 which is a quarter of an inch in front of the base of the rear casing 10. The rear flange 32 of the upper transverse member 19 associated with the magazine 17 is provided adjacent the upper edge of the slot 35 with a forwardly projecting finger 39 which is a quarter of an inch in depth from front to rear. When the magazine 17 is in its operative position, this finger 39 rests on the cranked portion of the limb 37 of the attachment bracket 35 and the forward edge thereof abuts against the shoulder 38 on the bracket so as to positively locate the magazine 17 in its operative position.

The magazine 17 can be released by merely lifting the magazine so that the forward edge of this finger 39 is clear of the shoulder 38 on the attachment bracket whereupon the magazine can be pivoted forwardly about the spindle 22. The third limb 40 of the attachment bracket 35 provides a stop and the length of the limb 37 is such that when the forward edge of the finger 39 on the upper transverse member rests against the limb 40, the magazine 17 is supported in an inclined position with respect to the casing, so that the upper or loading end thereof is fully exposed thereby enabling the magazine to be

readily filled, such position being shown in chain dotted lines in the upper portion of FIGURE 2.

As will be seen from FIGURE 2, the limb 40 terminates a short distance below the end of the casing so that, if desired, the magazine may be lifted clear of the casing. It will of course be appreciated that as the angle section plate 23 supports the articles in the magazine, the magazine will only be removed from the casing when it is completely empty.

With a delivery mechanism of the type shown in FIGURES 1 and 2, there is a tendency for the articles 21 to be lifted in the magazine during the delivery operation and, in order to hold the magazine 17 firmly in its operative position, the upper end of the magazine is provided with an angle section bracket 41 which extends out to one side of the magazine. This bracket 41 includes an arm 42 which is disposed in a horizontal plane when the magazine is in its operative position, this arm 42 being formed on its upper surface with a locating groove 43. This bracket 41 is so positioned that the one securing stud 44 associated with the outer casing 11 is adapted to engage in the groove 43 when the outer casing is in position. Thus, when the outer casing is in position, the magazine 17 cannot lift due to the abutment between the bracket 41 and the stud 44 but when it is desired to reload the magazine the outer cover will, of course, be removed so that the magazine can be lifted and moved into its inclined or loading position.

If desired, the magazine may be retained permanently in the machine and to this end the construction shown in FIGURE 5 is adopted. As seen in FIGURE 5, the one limb 40 of the magazine attachment bracket 35 is extended so that it abuts against the upper end of the outer casing 11, the limb 40 being actually secured to the end of the inner casing 10 as indicated by the weld 45.

In the construction shown in FIGURES 6 to 8, the magazine 17 is divided into three compartments 46, the magazine being adapted for the storage of relatively small articles such as packets of chewing gum. The delivery spindle 47 is of the continuously rotatable type, that is to say, after delivery of an article the spindle will lock and can then be released, upon insertion of the appropriate coinage, so that further rotation through a predetermined angle will deliver a further article. The spindle 47 is provided with three pairs of delivery fingers 48, 49 and 50, the individual pairs of delivery fingers being in register with the three compartments 46 as is clearly seen from FIGURE 6. As seen from FIGURE 7, the individual fingers are spaced angularly around the spindle 47 by 60° and operation of the delivery mechanism is as follows. In response to successive insertions of the correct coinage the one finger 49 will deliver an article from the centre compartment 46; the next rotation of the spindle 47 will cause the one finger 50 to deliver an article from its associated compartment whilst the next rotation 55 will cause the one finger 48 to deliver an article.

In order to support the article in the magazine the lower end thereof is inturned, as shown at 51, suitable slots 52 being formed in this inturned base 51 and in the rear wall of the magazine so as to permit movement of the delivery fingers through the magazine.

With such a construction of magazine, the articles are self supporting in the magazine, so that the shopkeeper or other operator of the machine can keep a spare magazine ready loaded which can then be inserted in the machine at the appropriate time. In order, therefore, to facilitate removal of an empty magazine and replacement with a full magazine, the front limb 40 of the attachment bracket 35 for the upper end of the magazine is cut off short as clearly seen in FIGURE 8. The front limb 40 serves to support the magazine in an inclined or loading position, should it be desired to reload the empty or partially empty magazine but permits ready removal of the entire magazine should this be desired.

What I claim then is:

1. A coin vending machine comprising a casing, a

magazine mounted in said casing, the magazine being formed with guides defining a plurality of columns in which the articles to be delivered by the machine can be stacked, an article delivery mechanism and release mechanism operable in response to insertion of the correct coinage into the machine to release the article delivery mechanism and deliver the lowermost article from a column, and in which:

- (a) the article delivery mechanism includes a rotatable spindle having spaced article ejector fingers and means to actuate said spindle
- 10 (b) said magazine having means cooperating with said spindle to pivotally mount said magazine on said spindle,
- (c) the magazine and casing are provided with cooperating means adapted to enable the magazine to be supported in and moved between an operative position and a loading position.

2. A coin vending machine according to claim 1 in which the co-operating means of the magazine and casing include a first bracket mounted on the casing which bracket is provided at one end with a portion which extends into contact with the casing so as to prevent complete removal of the magazine and in which the upper end of the magazine is provided with a second bracket having a slot through which said first bracket extends.

3. A coin vending machine according to claim 2 in which said first bracket is provided with a shoulder adjacent the casing of the machine and said second bracket is provided with a finger adjacent the aforementioned slot, 30 said finger being adapted to be located against said shoulder when the magazine is in its operative position.

4. A coin vending machine according to claim 3 in which the upper end of the magazine is provided with a bracket member on said second bracket adapted to abut against a stop mounted on said casing of the machine, so as to positively locate the magazine against movement when in its operative position, the stop consisting of a locating stud secured to the casing and adapted to engage said bracket member when the machine is in its assembled operative state.

5. A coin vending machine according to claim 1 in which the lower end of the magazine is provided with an inturned base so that articles may be supported by the magazine when it is taken out of the machine, slots being formed in the base through which said article ejecting fingers may pass.

6. A coin vending machine according to claim 1 wherein said co-operating means includes a bracket in which one end of the bracket provides an abutment against which the magazine may rest when in the loading position, said abutment retaining the magazine in the loading position but permitting removal of the magazine from the machine.
